United States Patent Office

Des. 227,687
Patented July 10, 1973

227,687

SNOW VEHICLE

Donald Huffman, Montreal, Quebec, Canada, assignor to
Coleco Industries, Inc., Hartford, Conn.

Filed Apr. 5, 1972, Ser. No. 241,497

Term of patent 14 years

Int. Cl. D21—01

U.S. Cl. D34—15 AK

FIG. 1

FIG. 2

FIG. 3

FIG. 4

FIG. 5

FIG. 1 is a top plan view of a snow vehicle showing my new design;

FIG. 2 is a side elevational view thereof, the opposite side view being a mirror image thereof;

FIG. 3 is a rear end elevational view thereof;

FIG. 4 is a bottom plan view thereof; and

FIG. 5 is a front end elevational view thereof.

I claim:

An ornamental design for a snow vehicle, as shown.
